UNITED STATES PATENT OFFICE.

CHARLES F. SCHNEIDER, OF SPRINGFIELD, OHIO, ASSIGNOR TO THE ROBBINS & MYERS COMPANY, A CORPORATION OF OHIO.

COMMUTATOR.

1,210,703.

Specification of Letters Patent.

Patented Jan. 2, 1917.

Application filed July 21, 1914. Serial No. 852,321.

To all whom it may concern:

Be it known that I, CHARLES F. SCHNEIDER, citizen of the United States of America, residing at Springfield, county of Clark, and State of Ohio, have invented certain new and useful Improvements in Commutators, of which the following is a full, clear, and exact description.

This invention relates to an improvement in electric machines which embody an armature comprising commutator structure.

One of the objects of the present invention is to simplify the construction of the armature of electric machines; and at the same time to increase the durability and efficiency of the machine by providing for dependable mechanical connections and highly efficient electrical connections between the armature, commutator and the respective armature leads.

It is another object of the present invention to provide an armature for an electric machine, having simplified commutator structure, whereby the assembling and disassembling of the commutator and the armature will be greatly facilitated, and the cost of manufacture of the said parts materially reduced.

In the construction and manufacture of electric machines which embody armature structure, it will be understood that the sizes of the armature will vary in accordance with the size of the machine, and, of course, the commutator structure, including the conductive segments and the insulating portions will consequently vary in proportion.

Heretofore, it has generally been the practice to construct the commutator bar or segment from a solid piece of stock having conductive properties, and to then provide some means to secure the armature lead to said bar or segment, in order to effect the desired electrical connection.

From the above it will be noted that in armatures through which a heavy current is to flow, the commutator must be of much heavier conductive material than where the armature is adapted to pass only a small amount of current.

In the present invention, a given size stock is selected for the manufacture of commutators, and this is punched or formed into stock parts, so that in building up the commutator segments for armatures, through

which different current values are to pass, a more or less number of these punchings or formed pieces may be combined together to form the segments of the commutator. As a general rule, the segment heretofore employed has been formed of a single solid piece of stock and has been provided with an upwardly projecting portion, which is of substantially the same width as the segment to which the armature lead is secured in any desired manner. The present invention eliminates the necessity for forming the commutator segments with an upwardly projecting tang or end portion, by providing a pair of binding plates for each segment. Each of these binding plates is provided with a tang or projection at one end, and so arranged that the armature lead may be placed directly in good electrical contact with the punched elements which form the commutator segments and then these tang portions of the binding plates are bent in upon the armature lead, to form a firm mechanical connection, and at the same time to provide an extremely efficient electrical connection.

Further objects and advantages of the present invention will be apparent from the following description, reference being had to the accompanying drawings, wherein a preferred form of one embodiment of the present invention is clearly illustrated.

In the drawings: Figure 1 is a view in elevation of an armature embodying the present invention. Fig. 2 is a vertical sectional view taken on the line 2--2 of Fig. 1. Figs. 3 and 4 are detail views of certain of the elements shown in Figs. 1 and 2.

Referring to the drawings, the numeral 20 designates an armature for an electric machine having a suitable winding 21, which is carried upon a core formed upon the shaft 22. The commutator structure of the armature, designated by the numeral 23, comprises a plurality of segments, as is usual in the construction of commutators, but each of these segments in turn preferably comprise a plurality of different elements.

Referring to Fig. 2, an end view of an armature is clearly shown, wherein each of the commutator segments comprises a plurality of conductive elements 24 and a pair of binding plates 26, which are so arranged that a tang or projecting portion 27, formed

on each of said binding plates, will be in such position as to be bent down on the armature lead, once it has been placed in contact with the conductive segments 24. 5 Between each of the adjacent segments, suitable insulation 27^a is provided in the usual manner.

By referring to Fig. 4 it will be understood that the size of the segment may be 10 varied within extended limits, by the simple addition of more conductive elements to the respective segments. For instance, if the commutators must have segments of sufficient conductivity to carry a given amount 15 of current, the number of conductive elements making up each of the commutator segments may be readily determined.

By constructing the binding plates of a light material, it will be seen that the necessity 20 for providing a tang portion for each of the commutator segments, of substantially the same width as the segment itself, is eliminated, thus permitting a substantial saving in the construction of the segment.

25 Of course, when the leads have been placed in proper position, and the tang or projections of the binding plates bent down upon said leads, solder is applied to the assembly so as to insure the mechanical connection.

30 By reference to Fig. 2, it will be readily seen that the armature lead is brought directly into contact with the entire upper surface of each of the elements which comprise the segment.

35 While one of the preferred embodiments of the present invention has been described and illustrated, it will be understood that the right is reserved to make whatever changes and alterations, either in the construction of 40 the various elements, or the combinations thereof, as may come within the scope of the invention, as set forth in the appended claims.

What I claim is as follows:—

- 45 1. A commutator having segments, each of which comprises a plurality of individual conductive elements, and binding plates, intermediate of which said elements are positioned.
- 50 2. In an armature for electric machines, a commutator having segments each comprising conductive elements; binding plates positioned on either side of said conductive elements and having projections; and armature leads adapted to be secured by said pro-

jections and connected with the conductive elements.

3. In an armature for electric machines, provided with windings and leads therefor; a commutator having a segment comprising 60 a plurality of conductive elements; and binding plates in contact with said conductive elements and having flexible projections between which the armature leads may be clamped securely in contact with the conductive elements.

4. In a commutator, a commutator bar comprising a plurality of individual elements having a plain contacting surface; and means adjacent thereto having provisions for holding lead wires in direct contact with the individual elements of the commutator bar. 70

5. In an armature for electric machines provided with windings and leads therefor; 75 a commutator having segments each comprising conductive elements; and binding plates in contact with said conductive elements throughout the length thereof and having projections between which the armature leads are held in contact with said binding plates and the conductive elements. 80

6. In an armature for electric machines, a commutator having segments each comprising a conductive element, and binding 85 plates in contact with said conductive element having projections of less width than the conductive element; and armature leads adapted to be secured between said projections by bending said projections upon said 90 leads, whereby the armature leads are forced into direct contact with the conductive element and are also maintained in contact with the binding plates.

7. In an armature for electric machines, 95 provided with windings and leads therefor; a commutator having bars, each comprising a plurality of conductive elements; and a pair of binding plates of less transverse diameter than said conductive elements and 100 adapted to electrically connect the leads of said windings in direct contact with the conductive elements.

In testimony whereof I affix my signature in the presence of two subscribing witnesses. 105

CHARLES F. SCHNEIDER.
